DETACHABLE FURNITURE POST MOUNTING

Filed May 25, 1923

*Inventor.
Frank Kusterle.*

Fisher Towle Clapp & Son ^{Estab.}

UNITED STATES PATENT OFFICE.

FRANK KUSTERLE, OF KENOSHA, WISCONSIN, ASSIGNOR TO SIMMONS COMPANY, OF KENOSHA, WISCONSIN, A CORPORATION OF DELAWARE.

DETACHABLE FURNITURE-POST MOUNTING.

Application filed May 25, 1923. Serial No. 641,294.

To all whom it may concern:

Be it known that I, FRANK KUSTERLE, a citizen of the United States, residing at Kenosha, in the county of Kenosha and State of Wisconsin, have invented certain new and useful Improvements in Detachable Furniture-Post Mountings, of which the following is a specification.

My invention relates to improvements in post mountings and is of particular service in connection with mirrors.

The principal objects of the invention are to provide a construction embodying in a single mounting means for holding down the table sheet, securing the pedestal or wall in position and mounting the post by which a mirror or other article is supported; to provide an improved construction in which the means for effecting the necessary connections are concealed, thereby not affecting the appearance of the furniture; to provide an arrangement which will permit of ready detachability of the post from the dresser or other piece of furniture by which it is supported; to provide an arrangement in which the dismounting of the post can be effected without the use of tools or mechanical equipment of any kind; to provide an arrangement which will be peculiarly well fitted to pieces of furniture in which the frame or other members are constructed of hollow sheet metal, for example tubing; to provide a construction which will not interfere with the design of the piece to comply with aesthetic requirements; to provide a construction which shall be simple in design and to manufacture, economical, exceptionally sturdy and rigid, fool proof and efficient, and in general to provide an improved construction of the character referred to.

In the drawings which, by way of example illustrate my invention as applied to a steel dresser piece provided with mirror posts,

Fig. 1 is a fragmentary vertical section through the post, pedestal rail and dresser top.

Fig. 2 is a section taken on the line 2-2 of Fig. 1.

Fig. 3 is a section taken on the line 3-3 of Fig. 1.

Fig. 4 is a section taken on the line 4-4 of Fig. 1, and

Fig. 5 is a perspective of a section cut 55 from the end of the pedestal rail before assembly into the piece.

Referring to the drawings, the element 10 represents the back part of the framing which supports the table sheet 11 of the dresser top. Said member 10 in the present instance comprises a steel tube of rectangular cross section, said member extending along the back of said dresser under the pedestal rail or back wall 12 which overlies the rear margin of the table sheet 11. In the present instance said pedestal rail 12 is constructed of light steel tubing of substantially rectangular cross section recessed as indicated at 13 in order to provide an 70 ornamental panel like effect. The top and bottom sides 14 and 15 are preferably flat as shown.

The pedestal rail 13 and the frame member 10 are drawn or clamped together and in so doing clamp between them the table sheet 11 and the strip of deadening material for example felt or card board 16 which minimizes the metallic clang which would otherwise be present due to the hollow sheet metal construction. Said clamping means is located vertically beneath the base of the mirror post designated as a whole 17 and concealed by the base portion 18 thereof so that when the mirror post is in place no unsightly securing devices are in evidence. The same concealed effect applies to the means employed for securing the mirror post itself in position.

Describing first the means for clamping the pedestal rail 12 down upon the dresser top, it will be observed by reference to Fig. 5 that in the bottom and top sides of the rail 12 there are punched aligned circular apertures 19 and 20, the punch for making such apertures being equipped with means for forming sets of integral inwardly extending tongues 21. After the holes 19 are punched in the rail, a tubular spacer 22 is inserted in the tube with its axis aligned with said apertures 19 and 20 and the tongues 21 are bent inwardly so as to position and lock said spacing member 22 securely within the pedestal rail 12.

The table sheet 11, deadening strip 16 and upper wall 23 of the frame tube 10 are also apertured to align with the aperture 20 in the bottom side 15 of the rail

12 and there are also formed in the said top wall 23 of the frame tube 10 a pair of spaced diametrically opposed apertures as at 24. The bottom wall 25 of said frame tube 10 is also apertured as indicated at 26 in addition to which the opposite edges of said aperture 26 are bent upward slightly as indicated at 27. Before the frame tube 10 is assembled in the frame of the piece, 10 a pair of nut members 28 and 29 are slid into the tube 10 in position to register with the apertures previously described. Said lower nut 28 comprises a substantially square washer of fairly heavy sheet steel 15 having its central portion dished upwardly as shown at 30, the central part of said dish portion 30 being pressed or punched downwardly as shown at 31 so as to furnish extra stock for the internal threads 32 of 20 said nut. The width of the nut 28 is such as to slide rather loosely in the tube 10 while, of course preventing same from turning in the tube.

The upper nut 29 is also formed square 25 to fit loosely the interior of the tube 10 in addition to which there are formed on the sides of said nut 29 oppositely disposed turned down flanges 33 adapted to rest upon the edges of the bottom nut 28 and being of such length as to prevent the said lower nut 28 from losing its interlocking 30 engagement with the lugs 27 of aperture 26. The central portion of the nut 29 is punched downwardly nipple fashion as 35 shown at 34 to provide extra metal for the threads 35 of said upper nut. A pair of apertures as at 36 are also formed along the median line of said nut 29 to register with the apertures 24 in the top wall 23 of the 40 frame tube 10. It will be understood that after the parts 28 and 29 have been introduced into the tube and placed in register with the apertures therein, the edges of the apertures 24 which are considerably 45 smaller than the apertures 36 are pressed downwardly as by a conical punch, into the apertures 36 of nut 29 thereby securely and permanently locking the said nut 29 and also through it the nut 28 in position in 50 said frame tube 10.

The member 37 is a metal sleeve or tubular screw having its lower end externally threaded as indicated at 38 to fit the internal threads 35 of the upper nut 29. The 55 upper end of said tubular screw 37 is formed square as indicated at 39 to enter a correspondingly shaped aperture in a rather heavy circular washer 40 of considerably greater diameter than the diameter of the aperture 19. The protruding end of said square portion 39 is riveted or expanded over the upper side of washer 40 as indicated at 60 41, thereby locking said parts 37 and 40 rigidly together so that washer 40 constitutes in effect a head for the tubular screw 65

37. Said parts 37 and 40 may also be brazed or welded together at the joint to provide additional strength.

It will be manifest that a plug wrench or key may be inserted in the square aperture 70 in the upper end of the tubular screw 37 thereby enabling the said screw to be turned and set up by thus drawing the said parts 12 and 10 firmly together and solidly clamping the table sheet 11 therebetween. 75

The mirror post, designated as a whole 17, to satisfy the æsthetic requirements, is made somewhat tapered and also tubular as shown at 42. Said tapering portion does not extend down all the way to the top of 80 the pedestal rail 12, but is carried on the top of an intermediate mount comprising a metal shell 43. Said shell 43 is suitably shaped to conform with the ideas of the artist who designed the piece and has at 85 its lower end an enlargement or skirt 44 fitting over, enclosing and aligning head 40 of the rail clamping screw. On the upper end of said mount 43 there is also formed a short barrel portion 45 fitting 90 snugly within the open lower end of the tapered portion 17 of the post.

The means for securing the mirror post comprises as the principal elements, a central bolt having its axis aligned with the mirror post tube 42, said bolt 46 being of the right diameter to slide through the tubular clamping screw 37. The lower end of said bolt 46 is threaded to fit the internal threads 32 of nut 28 and the upper end of said bolt 46 is made with a head 47 and a square neck portion 48 to fit a similarly shaped aperture punched in a filler cup 49 brazed or otherwise rigidly secured in the lower end of the mirror post tube 42. 105

It will be observed that the end 50 of the barrel shaped portion 45 of the mount 18 is apertured to admit the stem of bolt 46, which stem is additionally guided in a central aperture punched in a stiffening disk 110 51 fitting within a suitable circular seat 52 in the interior of the mirror portion of the mount 18 and brazed to the bolt 46 which is thus locked in the post, and secures the mount on said post. 115

Ordinarily, the dresser or other piece to which my invention is applied, is shipped knocked down, that is to say, with the mirror and its supporting posts removed. However, it is generally thought advisable to ship the piece with the pedestal rail or back wall member 12 in place. My construction fully satisfies these requirements since the mirror post can readily be moved by simply grasping the tapered portion 17 120 and thus unscrewing the bolt 46 from nut 28 whereupon the mirror post and mount 43 may be dismounted. Removal of the mirror post does not in any way affect the rigid connection between the pedestal rail 125 130

12 and the frame tube 10 since such parts have their own independent connection through tubular screw 37. Also it will be observed that the mounting of the mirror 6 post 17 in position on the pedestal rail 12 effectively conceals the head 40 of the means employed for securing said pedestal rail 12 to the dresser top.

The described details of construction being illustrative of merely one application of my invention, the scope of same should be determined by reference to the appended claims, said claims being construed as broadly as possible consistent with the state 15 of the art.

I claim as my invention:

1. In metal furniture, the combination of a frame member, a wall member over said frame member, a table sheet interposed between 20 said two members, a tubular screw connecting said members for drawing said members together, a standard mounted on the top of said wall over said screw and means extending through said screw for securing said standard to said wall.

2. In metal furniture, the combination of a body frame member, a hollow wall member above said frame member, a table sheet interposed between said two members, a tubular screw connecting said members having a head above the top of said wall member and extending into said body frame member, for drawing said two members together, a standard supported on the top of 35 said wall member and having at its lower end a recess enclosing said head and means extending through said tubular screw for clamping said standard on said wall.

3. In metal furniture, the combination of 40 a hollow body frame member, a hollow wall member above said frame member, a table

sheet interposed between said two members, a tubular screw for drawing said members together and having a head engaging the top surface of said wall member, and a nut 45 mounted in said body frame member, a standard mounted on the top of said wall, and a bolt extending through said screw and connected to said standard for clamping said standard on said wall.

4. In metal furniture, the combination of a hollow body frame member, a hollow wall member above said frame member, a table sheet interposed between said two members, a tubular screw for drawing said members together and having a head engaging the top surface of said wall member, and a nut 50 mounted in said body frame member, a standard mounted on the top of said wall, a bolt extending through said screw and connected to said standard for clamping said standard on said wall and a nut for said bolt under said first nut.

5. In metal furniture, the combination of a hollow body frame member, a hollow wall member above said frame member, a table sheet interposed between said two members, a tubular screw for drawing said members together and having a head engaging the top surface of said wall member, and a nut 65 mounted in said body frame member, a standard mounted on the top of said wall, a bolt extending through said screw for clamping said standard on said wall, and a non-rotary nut for said bolt under said 70 first nut, said bolt having a head secured in said standard against axial movement and rotation therein, whereby rotation of said standard will serve to clamp the same on said wall.

FRANK KUSTERLE.
